UNITED STATES PATENT OFFICE.

JOSEPH C. HITCHNER, OF HAMMONTON, NEW JERSEY, ASSIGNOR TO CHENEY TALKING MACHINE COMPANY, OF CHICAGO, ILLINOIS, A CORPORATION OF ILLINOIS.

REPEATING MECHANISM FOR TALKING MACHINES.

Application filed June 4, 1920. Serial No. 386,540.

To all whom it may concern:

Be it known that I, JOSEPH C. HITCHNER, a citizen of the United States, residing at Hammonton, county of Atlantic, State of New Jersey, have invented a new and useful Repeating Mechanism for Talking Machines, of which the following is a specification.

My present invention comprehends a novel construction and arrangement of a repeating mechanism for talking machines whereby after the placing of a record the sound box will be automatically lifted from the record, automatically returned to its initial or starting position and automatically lowered to bring the stylus into engagement with the record to enable the immediate replaying of the same selection.

It further comprehends a novel construction and arrangement of controlling devices which are automatically set into operation when the stylus of the sound box has reached the limit of its travel in the impression grooves of a record so that the other portions of the repeating mechanism are operatively connected with the motor, the parts being timed in such a manner that the sound box is first lifted from the record, then returned to its initial or starting position, and then lowered to cause the stylus of the sound box to re-engage the first impression grooves of the record.

Other novel features of construction and advantage will hereinafter more clearly appear in the detailed description of the invention.

For the purpose of illustrating my invention, I have shown in the accompanying drawings a typical embodiment of it which is at present preferred by me, since such embodiment will give in practice satisfactory and reliable results. It is, however, to be understood that this embodiment is typical only and that the various instrumentalities of which my invention consists can be variously arranged and organized and that the invention is not limited to the precise arrangement and organization of these instrumentalities as herein set forth.

Figure 1 represents a top plan view of a repeating attachment for talking machines, such attachment being shown in assembled position with respect to the talking machine.

Figure 2 represents a section on line 2—2 of Figure 1.

Figure 3 represents a section on line 3—3 of Figure 2.

Figure 4 represents a front elevation of a mutilated gear employed.

Figure 5 represents a section on line 5—5 of Figure 2.

Figure 6 represents a section on line 6—6 of Figure 5.

Figure 7 represents a section on line 7—7 of Figure 2.

Figure 8 represents a section on line 8—8 of Figure 2.

Figure 9 represents a section taken in the same line of Figure 8 but showing the parts in different relation from each other from 70 that shown in Figure 8.

Similar numerals of reference indicate corresponding parts.

Referring to the drawings.

1 designates the casing of a talking machine which may be of any desired or conventional construction. The talking machine is provided in the usual manner with a motor 2 which is operatively connected with a turn table shaft 3 in order to rotate it, and thereby the turn table 4 carried by said shaft 3. The talking machine is provided in the usual manner with a tone arm 5 to which is connected by means of a neck 6 the sound box 7 which latter is adapted to receive a stylus 8. The turn table shaft 3 has a gear 9 adapted to be engaged at certain times with a mutilated gear 10, the detailed construction of which will be more clearly seen in Figure 4. This mutilated gear 10 is fixed to a shaft 11 mounted in journals 12 carried in any desired manner by a fixed portion of the talking machine. The shaft 11 has fixed to it an eccentric 13 which travels within an eccentric strap 14 the internal contour of which is preferably rectangular, as will be best understood by reference to Figure 3. The strap 14 has swiveled in it the head 15 of a rod 16 which latter is journaled in a bearing sleeve 17 and is provided with a pin 18 which extends into a slot 19 in the sleeve 17. The sleeve 17 is provided with a collar 20 rotatably mounted in a bearing 21 carried by the casing 1.

The upper end of the rock shaft 16 is 105 bifurcated as indicated at 22 to receive one end of a lever 23 which is pivoted to the bifurcated portion 22 by means of a pin 24. The lever 23 is provided with a U-shaped portion 25 which rests on the tone 110

arm 5 and terminates in a curved arm 26 which bears against the neck 6 in order to effect at the proper time the lifting or lowering of said goose-neck and thereby of the sound box carried by the neck.

The tone arm 5 is provided with an adjusting screw 27 adapted to engage an arm 28 one end of which is pivoted in a rock shaft 29 rotatably mounted in the casing 1.

10 The lower end of the rock shaft 29 is provided with a hemispherical portion 30 which partially surrounds the shaft 11 and the shaft 11 is provided with an arm 31 which co-operates at certain times with the hemispherical portion 30 and with the rock shaft 29 as will hereinafter appear in the detailed description of the operation of my invention.

20 The bearing sleeve 17 at its lower end is provided with a laterally extending rod 32 having at its free end a head 33, and mounted to slide on the rod 32 is a shoe 34 having the upwardly extending spaced pins 35 and a downwardly extending arm 36, see in particular Figures 2 and 7.

30 The shaft 11 has adjustably mounted thereon a plurality of cams the number of which depends upon the different sizes of the records which are to be played and since the records commonly employed are either ten inch or twelve inch records, I have shown two cams, the cam 37 being for a ten inch record and the cam 38 being for a twelve inch record. It will of course be understood that any desired number of cams may be employed. These are adjustably positioned on the shaft 11 by means of a set screw 40. Positioned between the pins 35 is a curved arm 41 having at one end the stops 42 and connected at its opposite end to a rotatable adjustable arm 43 which is journaled in the casing 1 and provided with an actuating handle 44. This operating and adjusting handle 44 is provided with a pointer 45, and a disc 46 is provided having calibrations 47 so that the operator can readily adjust the rod 43 to cause the arm 36 to cooperate with the proper cam such as 37 or 38 in accordance with the size of the record which is being played.

45 The operation of my novel repeating attachment for talking machines will now be readily apparent to those skilled in the art to which this invention appertains and is as follows:—

50 The arm 28 if it is thrown over out of the path of the adjusting screw 27 will be in its inoperative position and the talking machine will operate in its usual manner, as if no repeating attachment were present. If, however, this arm 28 is thrown over into the position seen in Figures 1 and 2, the travel of the tone arm 5 due to 55 the engagement of the stylus 8 with the

impression groove of the record will bring the adjusting screw 27 into contact with the arm 28 as the stylus reaches the end of the impression groove of the record. This engagement of the adjusting screw 27 with the arm 28 causes a partial rotation of the rock-shaft 29 so as to effect a release of the stop 31 on the shaft 11. The eccentric 13 is weighted as at 48, see Figure 3, so that as soon as the stop formed by the arm 31 is released the shaft 11 will be sufficiently rotated to bring the teeth of the mutilated gear 10 into mesh with the gear 9 on the turntable 3, so that one revolution is imparted to the shaft 11. It will be seen that the rock shaft 29 has an off-set from which extends a curved arm 30 so that as the stop 31 revolves about one-half a revolution from the position seen in Figure 5, it will co-operate with the curved arm 30, which when the rock shaft 29 is rocked brings the free end of the arm 30 nearer to the shaft 11, so that the rock shaft 29 and its adjuncts will be returned to their initial position.

60 The eccentric strap 14 due to the rotation of the eccentric 13 causes a downward pull on the rod 16 thereby rocking the lever 23 to move its curved arm 26 into engagement with the neck and cause the neck to be raised thereby raising the stylus out of engagement with the impression groove of the record. This curved arm 26 of the lever 23 is normally out of engagement with the neck so that the rise and fall of the sound box during the playing operation is not interfered with.

65 The rotation of the shaft 11 causes the cams 37 and 38 to rotate in unison with it and assuming for example that the cam 37 is to effect the operation of transferring the sound box to its initial or starting position, this cam will contact with the arm 36 thereby rocking the rod 32 which is connected to the rotatable head or sleeve 17. Due to the manner in which the rod 16 is connected with the sleeve 17 this rocking or partial rotation of the rod 32 causes the tone arm and sound box to be returned to their initial or starting position, at 70 which time the eccentric 13 causes the rods 16 to move upwardly thereby permitting the stylus 8 to come into engagement with the record. As the turntable is continuously revolving the replaying of the same piece of the record will be effected.

75 The tone arm and sound box are prevented from being moved beyond their initial or starting position due to momentum by one of the stops 42 on the curved arm 41 and one of the pins 35 carried by the rod 32. The operation which has just been described relates to one side of the record, for example, a ten inch record. If it is desired to play a record of a different size, 80

such as for example, a twelve inch record, the handle 44 is actuated to bring the shoe 34 into such position on the rod 12 that the arm 36 will be in path of the cam 38 and 5 the operation just described will be repeated, the only difference being that the outer stop 42 contacting with the outer pin 35, see Figures 8 and 9, will limit the outward throw of the tone tube and sound box, as 10 will be apparent to those skilled in this art.

If the arm 41 is adjusted to its neutral position then the pins 35 will not engage with the stops 42.

Whenever the mutilated gear 10 is 15 brought into action it will be apparent that the shaft 11 will rotate until the dwell portion of the gear is brought into the path of the teeth of the gear 9 at which time the arm 31 comes into engagement with the 20 curved lower end of the rock shaft 29 and the repeating mechanism will be retained in its actuating position ready to be released again as soon as the rock shaft 29 is partially rotated due to the contact of the adjusting screw 27 with the arm 28.

It will be apparent that my novel construction of repeating attachment can be readily attached to the usual or conventional type of talking machine in which a 30 disk record is used since it is only necessary to secure the attachment in position, so that it will be intergeared with the turntable shaft.

It will now be apparent that I have devised a new and useful repeating mechanism 35 for talking machines which embodies the features of advantage enumerated as desirable in the statement of the invention and the above description, and while I have, in 40 the present instance, shown and described a preferred embodiment thereof which will be found in practice to give satisfactory and reliable results, it is to be understood that such embodiment is susceptible of modification in various particulars without departing from the spirit or scope of the invention or sacrificing any of its advantages.

Having thus described my invention, what I claim as new and desire to secure 50 by Letters Patent, is:—

1. In a repeating attachment for talking machines in combination, a tone arm and its neck, a lever fulcrumed on said tone arm to effect the raising and lowering of the neck at the proper time, a turntable shaft, a gear thereon, a second shaft, a mutilated gear on said second shaft co-operating with the turntable shaft gear and controlled by the position of the tone arm, a 55 connection from said lever to said second shaft to actuate said lever, and means actuated by said second shaft and co-operating with said connection to effect the return of the tone arm to its initial position 60 after a record has been played.

2. In a repeating attachment for talking machines in combination, a tone arm and its neck, a lever fulcrumed on said tone arm to effect the raising and lowering of the neck at the proper time, a turntable shaft, 70 a second shaft, a gear on said turntable shaft, a mutilated gear on said second shaft to co-operate with said gear and controlled by said tone arm, a connection from said lever to said second shaft to actuate said lever, and means actuated by said second shaft and co-operating with said connection to effect the return of the tone arm to its initial position after a record has been played, 75 said means being adjustable to vary the travel of the tone arm in its return movement and thereby adapt the feeding attachment to co-operate with records having different widths of impression grooves.

3. In a repeating attachment for talking machines, in combination, a tone arm and its neck, a lever fulcrumed on said tone arm to effect the raising and lowering of the neck at the proper time, a turntable shaft, 80 a second shaft, a gear on said turntable shaft, a mutilated gear on said second shaft co-operating with said turntable shaft gear and controlled by said tone arm, a connection from said lever to said second shaft to actuate said lever, means actuated by said second shaft and co-operating with said connection to effect the return of the tone arm to its initial position after a record has been played, 85 and means carried by said tone arm to control the operation of said second shaft.

4. In a repeating attachment for talking machines in combination, the tone arm and its neck, the turntable shaft, a second shaft, 90 a gear on said turntable shaft, a mutilated gear on said second shaft to co-operate with said turntable shaft gear and controlled by said tone arm, an eccentric on said second shaft, a lever carried by said tone arm actuated by said eccentric and controlling the raising and lowering of said neck, means actuated by said second shaft to effect the return of said tone arm to its initial position, and a manually actuated detent for said second shaft.

5. In a repeating attachment for talking machines in combination, the tone tube and its neck, the turntable shaft, a gear on said turntable shaft, a second shaft, a mutilated gear on said second shaft to mesh with said turntable shaft gear, an eccentric on said second shaft, a connection actuated by said eccentric, a lever carried by said tone arm operated by said connection and adapted to effect the raising and lowering of said neck, 100 a cam on said second shaft adapted to co-operate with said connection to effect the return of said tone arm to its starting position, a rock shaft co-operating with said second shaft to effect its starting and stop- 105

ping, and means carried by said tone arm to actuate said rock shaft.

6. In a repeating attaching for talking machines in combination, the tone tube and its neck, the turntable shaft, a gear on said turntable shaft, a second shaft, a mutilated gear on said second shaft to mesh with said second turntable shaft gear, an eccentric on said second shaft, a connection actuated by 10 said eccentric, a lever carried by said tone arm operated by said connection and adapted to effect the raising and lowering of said neck, a cam on said second shaft adapted to co-operate with said connection to effect 15 the return of said tone arm to its starting position, a rock shaft co-operating with said second shaft to effect its starting and stopping, an arm pivotally carried by said rock shaft, and means carried by said tone arm 20 to contact with said arm and actuate said rock shaft.

7. In a repeating attachment for talking machines in combination, the tone tube and its neck, the turntable shaft, a gear on said turntable shaft, a second shaft, a mutilated gear on said second shaft to mesh with the gear on said turntable shaft, an eccentric on said second shaft, a connection actuated by said eccentric, a lever carried by said 30 tone arm operated by said connection and adapted to effect the raising and lowering of said neck, a cam on said second shaft adapted to co-operate with said connection

to effect the return of said tone arm to its starting position, a rock shaft co-operating 35 with said second shaft to effect its starting and stopping, an arm pivotally carried by said rock shaft, means carried by said tone arm to contact with said arm and actuate said rock shaft, said arm when swung over 40 on its pivot being out of the path of said means.

8. In a repeating mechanism, in combination, a driving gear and a mutilated gear arranged to be engaged with said driving 45 gear, means normally restraining rotation of said mutilated gear, a tone arm, and a cam actuatable by said mutilated gear for effecting a return of said tone arm to initial position, said means being arranged to be 50 actuated by said tone arm to release said mutilated gear to engage the driving gear.

9. In a repeating mechanism, a tone arm, a driving gear, a mutilated gear normally disengaged from said driving gear, means 55 holding said mutilated gear in disengaged relation, said tone arm adapted to engage said means to release said mutilated gear, weight means biasing said mutilated gear to engage said driving gear, and cam means 60 operated by said mutilated gear to restore the tone arm to initial position.

JOSEPH C. HITCHNER.
